Patrick J. Regan, 12501 W. Bluemound Road,
Elm Grove, Wis.

Filed Aug. 7, 1961, Ser. No. 66,215

Term of patent 14 years

(Cl. D9—2)

FIGURE 1 is a perspective view of a bowling lane maintenance machine showing my new design;

FIGURE 2 is a top plan view thereof;

FIGURE 3 is a front elevational view thereof;

FIGURE 4 is a side elevational view thereof as seen from the right of FIGURE 3; and

FIGURE 5 is a rear elevational view thereof.

The dominant features of the design reside in the portions shown in full lines.

I claim:

The ornamental design for a bowling lane maintenance machine, substantially as shown and described.
